UNITED STATES PATENT OFFICE

2,373,746

COLLATOR

Albert Dager, Los Angeles, Calif., assignor of one-half to Elias Shaheen, Los Angeles, Calif.

Application August 17, 1943, Serial No. 498,928

5 Claims. (Cl. 271—62)

This invention constitutes an improvement upon my invention for collators, Patent No. 2,308,804, issued January 19, 1943. Particularly the present invention has to do with certain improvements in the bins for holding paper which is to be manifolded.

The bins of the present invention are so arranged as to be elevated as sheets in said bins are depleted during the collating sequence of operations, and an object of the invention is to provide a mechanism which is simple of structure and capable of performing the functions required in an expeditious manner.

The present device is useful in conjunction with the collator of my issued patent, particularly in small print shops which are unable to afford large collators. Collators are very expensive and cost several thousands of dollars, whereas the device of my invention, and particularly the patented structure, is capable of being built and sold for a few hundred dollars.

Objects of the invention include a structure which is simple, useful and generally superior to the devices now known to the inventor.

With the above mentioned objects in view, the invention consists in the novel and useful provision, formation, construction, association and relative arrangement of parts, members and features all as shown in a certain embodiment in the accompanying drawings, described generally and more particularly pointed out in the claims.

In the drawings:

Fig. 1 is a plan view of the improved bin mechanism;

Fig. 2 is a fragmentary side elevation of a pair of bins for holding sheets to be collated, together with the improved mechanism for actuating the bins;

Fig. 3 is a sectional view on the line 3—3 of Fig. 1; and

Fig. 4 is a fragmentary side elevation illustrating the operation of certain mechanism of the invention.

Referring now to the drawings, I provide two or more bins designated generally as 1 and 2, within which are placed stacked sheets as shown at 3 and 4, with single sheets adapted to be removed simultaneously from each bin and fed between means illustrated at 5 and 6 and finally deposited on a tray or on a table in manifold or collated form, which is to say the uppermost sheet from stack 4 would overlie a sheet from stack 3. Manifolding of sheets is essential for price books, sales books, and the like where a plurality of sheets must be used. Usually the sheets are of

different colors, such as white, red, green, blue, yellow, with carbon paper placed therebetween for making multiplices. It is essential that sheets from each bin should be properly fed to the mechanism 5 and 6, this mechanism following my invention illustrated and described in my Patent No. 2,308,804. This mechanism includes pairs of continuous belts 7 and 8, two reaches of each pair of belts being in contact, as shown at 9. The belts are passed around pulleys as shown at 10 and 11, and likewise driven by suitable mechanism not shown.

The bin constructions are identical, for which reason the bin at 2 will be described. This bin 15 includes a platform 12 which constitutes a substantially rectangular piece provided on its front edge with a narrow center extension 12a. The platform is adapted to hold the stock and the stock is held in proper position on the platform through the medium of stock guides 13 and 14. These stock guides are angled so as to guide the stock at the sides and front edges thereof. As stock varies in width, the guides 13 and 14 are made adjustable, being carried upon an oppositely pitched screw shaft 15, which is journaled between members 17 and 18 of a framing. The shaft 15 carries a crank 16, whereby upon turning the crank, the stock guides are caused to approach the front extension 12a or to separate therefrom.

The members 17 and 18 of the framing include in addition thereto uprights 19, 20, 21, 22, 23 and 24, the side members being suitably secured to said uprights. The uprights 20 and 23 are of angled formation, with one leg of each member received within a groove or way in members 25 and 26, the said last named members being secured to the sides of the platform 12. This construction assures that the platform will at all times move straight upwardly or downwardly without any longitudinal reciprocatory motion, in that the forward end of the platform will be held within the confines of the angle guides 13 and 14. The uprights 21 and 24 are angled in form, one leg of each thereof being secured to a side member 17 and 18, while the other leg of each member carries bearing blocks such as illustrated at 27 and 28. Parallel bearing blocks are adapted to accommodate a shaft 29 upon which a plurality of spaced pulleys 10 are mounted, as seen Fig. 1. This construction is adhered to for the other pulleys 11. The upright frame members 19 to 24 inclusive in turn are suitably supported on a table or other device, and reference is again made to my patent, supra. To as-

sure that the stack of sheets 4 remains in position on the platform and bears against the confining legs of guides 13 and 14, I have provided an adjustable end bracket 30. This bracket is of the usual construction, including a plate 31 secured to a slotted base member 32, with a bolt 33 passed through the slot 32 and carrying a wing nut 34.

As paper is fed from the stack 4 to the feed conveyor belts, it is essential that the stack be maintained at a selected elevation or height, to the end that the uppermost sheet of paper be at a given height with respect to a suction foot. This suction foot is shown at 35, and is connected with a hose 36, which leads to a pump (not shown). The foot is carried by a rod 37 which moves the suction foot into engagement with the forward end of the top of the stack of sheets, and then elevates the sheet to place it between a pair of the conveyor feed belts, at which time the suction to the foot is broken so that the sheet is released. As the suction foot has a definite up and down and reciprocatory movement, it is essential that the uppermost sheets of the stack be maintained at a substantial level and during depletion of the stack of sheets. To accomplish this, I provide mechanism of simple construction which has been found in actual practice to work satisfactorily. This mechanism includes a segmental ratchet 38 carried by arms 39 and 40 radiating from a hub 41. The hub is mounted upon a trunnion 42 of platform elevating means, designated generally as 43. This platform elevating means includes a rod so bent as to provide end trunnion 42 and a trunnion 44. The rod is then bent to provide two aligned and parallel legs joined with the trunnions, as shown at 45 and 46, and a connecting piece 47 between the legs. This connecting piece is provided with an intermediate crank portion 48. The trunnions are passed through suitable openings forming bearings for said trunnions in the side frame members 17 and 18. I provide a like elevating means 49 adjacent the forward end of the platform, the same reference characters applying to this elevating means as apply to the elevating means at 43. The crank portions 48 of the elevating means 43 and 49 are interconnected by an adjustable link 50, the said link being journaled to the crank portion 48 of means 49, and provided with edge slots 51 for adjustable engagement with the crank 48 of the means 43. It is intended that the two elevating means should move in substantial parallelism, although the said elevating means may be arranged at different angularities to tip the stock, through the adjustment permitted by the link. Rockably secured by means 52 to the upright 19 is a pawl 53. This pawl is adapted to have engagement with the teeth of the ratchet 38. The uppermost end of the pawl has a rod 54 secured thereto. This rod in turn having other pawl members, depending on the number of platforms, also secured thereto, the rod finally terminating and carrying an end roller or bearing 55 for engagement with a cam 56. In the position shown in Fig. 2, the cam holds the pawl 53 in engagement with a tooth of the ratchet, and when the cam is rotated, as hereinafter described, to the position shown in Fig. 4, the pawl is lifted from engagement with the ratchet. The tendency is for the ratchet to rotate anti-clockwise, viewing the figures, under the urgency of a coil spring 57, secured at one end to the side framing member 17 and at the opposite end to an arm 58, carried by hub 41.

Journaled between the uprights 20 and 23 is a shaft 59; an arm 60 is secured to said shaft, said arm carrying a roller 61. One end of said shaft carries arm 62, and a link type rod 63 is secured to arm 62, and carries at its lowermost end a roller or bearing 64, adapted to have engagement with cam 65. Cams 56 and 65 are mounted on shafts 66 and 67, respectively, which shafts carry sprocket wheels 68 and 69, respectively, there being a continuous chain 70 between said sprocket wheels.

The operation, uses and advantages of the invention are as follows:

If we consider movement of a single tray, the cams 56 and 65 are so arranged that when the pawl 53 is in engagement with a tooth of ratchet 38, roller 61 is out of engagement with the uppermost sheet of the stack of paper 4 during movement of the suction foot 35 to elevate a sheet 20 of paper and position the sheet between the conveyor belts. Both cams are being rotated by suitable means which drives one of the shafts 66 or 67, and when the cam 65 has rotated to a position which will elevate the rod 63, shaft 59 is 25 rotated through the medium of arm 62 to cause rotation of arm 60 and bring the roller 61 into engagement with the uppermost sheet of the stack of paper 4. At this time, cam 56 has rotated to a position to permit rod 54 to move 30 downwardly and release pawl 53 from ratchet tooth engagement, as illustrated in Fig. 4. The coil spring 57 urges rotation of the elevating means 43 by rotating trunnion 42. Whatever rotation occurs is immediately communicated by 35 link 50 to elevating means 49. Normally, when the platform is loaded with a stack of paper, the elevating means will have their leg portions 45 and 46 at a like angle relative to a horizontal plane, and as the sheets are fed from the top 40 of the stack, this angle between the legs and a horizontal plane will gradually increase until it reaches substantially 90 degrees. Such movement raises the platform. The cam 65 normally moves the roller 61 the same distance, thus assuring that the uppermost sheet of the stack will 45 always be at a certain height relative to the guides 13 and 14, and quite obviously when the roller 61 is in engagement with the uppermost sheet of the stack of paper, as shown in Fig. 4, the platform is prevented from moving upwardly, save and except for a selected elevation, with the result that the spring 57 does not cause a complete movement of the ratchet. Prior to the 50 wheel 61 being released from engagement with the stack of sheets 4, the pawl 53 engages a tooth of the ratchet, whereupon the wheel 61 is released so that the suction foot may engage the uppermost sheet for feeding purposes.

As previously stated, the other bins are spaced- 55 ly arranged one above the other, and the platforms of all the bins are actuated in the manner just described. It is also evident that the stack of paper in one bin may not be of the same height as the stack of paper in another bin, because adjustment is permitted automatically by the rollers 61. If one stack, say, is three inches in thickness and the second stack is one inch, when the pawls are elevated from ratchet engagement, the platform carrying the stack of lesser depth will move upwardly until the uppermost sheet thereof engages its roller, and then movement is stopped, for the reason that the coil spring 57 will rotate the ratchet and its shaft 41, to in turn rotate both elevating means upwardly 60 to position the platform at the desired height.

It is apparent that both the arms 62 and the pawls 53 will have an arc of movement during reciprocal rotation thereof, which will move the rods 54 and 63, but this lateral movement will have no effect upon the operation of the mechanism, as the cams are so arranged as to compensate for any such movement and provide for a proper sequence of operation.

I claim:

1. In a device as disclosed, a pair of spaced bins for holding stacked paper which is to be manifolded, each bin having a platform, and means for each platform for elevating the same to maintain the stacked paper at a selected height, the said means comprising a pair of spaced cranks beneath a platform, means interconnecting the cranks for maintaining the same at an angularity relative to its platform, a segmental ratchet secured to one of said cranks, a pawl for engagement with the ratchet, cam means for rocking the pawl to release the same at certain intervals from the ratchet, and means normally urging the ratchet to rotate in one direction.

2. In a device of the character disclosed, a platform upon which stacked paper may be placed, a pair of spaced levers engageable with said platform, rotation of which levers raises or lowers the platform, a segmental ratchet secured to one of said levers, and means normally tending to rotate said ratchet and said lever to cause elevation of the platform, a pawl engaging said ratchet to control rotation thereof, a pair of cams, one of said cams actuating said pawl to either cause engagement thereof with the ratchet or release from the ratchet, a swing lever for engagement with said stack of paper controlled as to movement by said second cam, the relationship being such that when the cam releases the pawl from the ratchet, the second cam brings its associated lever into engagement with the stack of paper, and upon engagement of the pawl with the ratchet, the second lever is released from the stack of paper.

3. In a device of the character disclosed, a framing, a platform, and means secured to the framing for guiding up and down movement of the platform relative to the framing, swing levers pivoted in the framing and engageable with said platform for raising and lowering the platform, a segmental ratchet secured to one of said

levers, means for urging one of said levers to rotate and cause elevation of the platform, a pawl engaging the ratchet for restraining rotation of the ratchet, a pair of spaced interconnected cams, one of which controls movement of said pawl, a swing lever pivoted in the framing for engagement with the platform and adapted to be controlled as to movement by the second cam, the relationship being such that when the second lever is in engagement with the platform, the pawl is out of engagement with the segmental ratchet, and vice versa.

10 4. In a device of the character disclosed, a platform upon which stacked paper is placed, swing levers for said platform for raising or lowering the same, a lever for engagement with the top of said stack of paper, means causing rotation of said swing levers to raise the platform, said means comprising a ratchet secured to one 15 of the said swing levers, a pawl for engagement with said ratchet, and cam means for releasing the pawl from ratchet engagement and moving the lever into engagement with the top of the stack of papers and for causing disengagement of the lever from the top of the stack of papers when the pawl engages the ratchet, whereby the top of said stack of papers is maintained at a selected elevation.

20 5. In a device of the character disclosed, a platform, angle members engaging ends of said platform to guide raising and lowering movement thereof, levers for engagement beneath said platform for raising or lowering the platform, means interconnecting the levers causing like angular 25 movement thereof, said platform adapted to hold a stack of paper, a lever provided with a wheel in engagement with the uppermost sheet of said stack of paper, a first cam, a link connection between said lever and said cam, a second cam, a 30 pawl, and a link connection between said pawl and said second cam, and a segmental ratchet secured to one of the levers for elevating the platform, the relationship between the movement of the links upon turning the cams being such 35 that when the roller engages the top sheet of the stack of paper, the pawl is out of engagement with the ratchet, and vice versa, together with spring means for normally urging said levers to elevate the platform.

50

ALBERT DAGER.
